UNITED STATES PATENT OFFICE.

OCTER MAYFIELD, OF GRANITE, OKLAHOMA.

RAILROAD-TIE.

1,099,809.

Specification of Letters Patent.

Patented June 9, 1914.

Application filed September 25, 1913. Serial No. 791,836.

To all whom it may concern:

Be it known that I, OCTER MAYFIELD, a citizen of the United States, residing at Granite, in the county of Greer and State of Oklahoma, have invented certain new and useful Improvements in Railroad-Ties, of which the following is a specification, reference being had therein to the accompanying drawing.

10 This invention relates to metallic railway ties and has for its object the production of an improved tie having transversely extending slots forming rail-seats, and also improved means for holding the rail on the seat.

15 Another object of this invention is the production of an efficient tie that is adapted to be positioned at a joint of the rail and has a transverse slot or opening large enough 20 to accommodate the whole joint; namely, the rail and fish plate.

A still further object of this invention is the production of a combined nut lock and rail securing device adapted to be used with 25 a tie that is to carry a rail joint.

With these and other objects in view, this invention consists of certain novel combinations, constructions and arrangements of parts as will be hereinafter fully described 30 and claimed.

In the accompanying drawings:—Figure 1 is a perspective view of the track section showing the improved ties in use. Fig. 2 is a longitudinal section taken through one 35 end of the tie with the rail and rail securing means mounted thereon. Fig. 3 is a longitudinal section of the end of a tie adapted to secure a rail-joint with the joint and securing means mounted thereon. Fig.

40 Fig. 4 is a perspective view of a securing block used in this connection. Fig. 5 is a section taken on the line 5—5 of Fig. 3. Fig. 6 is a section taken on the line 6—6 of Fig. 2.

Referring to the parts by reference numerals, 10 denotes the tie proper having transversely extending slots 11, one side of 45 said slot 11 having an overhanging rail engaging tongue 12. This transversely extending slot 11 forms a rail-seat and the over-

hanging tongue 12 provides means for retaining the rail on the seat. Communicating with and extending at right-angles to, the slot 11, is a longitudinal under-cut slot 13 into which the rail securing block 14 is 50 adapted to be positioned. This block 14 is 55 provided with inclined side faces 15 which

engage the side faces of the slot 13 and said block 14 is provided with a beveled face 16 at its inner end, said beveled face 16 is adapted to engage the base of the rail. A 60 threaded opening 17 is formed in the block 14 and the set-screw 18 is adapted to be positioned therein to secure the block 14 in the slot 13. To facilitate the withdrawal of the block 14 from the slot 13, a cut-out portion 19 is provided so that an instrument of any kind may be inserted and the block withdrawn. Where the joining of two rails falls upon a tie, an enlarged transversely extending opening 20 is provided for in the 65 tie, as shown in Fig. 3 to accommodate both the rail and the fish plate. The enlarged opening 20 has an opening 21 communicating with and running at right-angles thereto, so as to provide means for the placing 70 of the block 14. The tie has a concave under face 22 and by the same provides means for securely anchoring the tie in the ballast, and also prevents the sinking of the same in the 75 ground.

It will be seen from the foregoing description that a railway tie has been provided so that the rail can be placed on the seat provided by the slot 11 and the block 14 is then positioned in the longitudinally extending slot 13 and forces the rail against the inner face of the overhanging tongue 12. A set-screw is then inserted and the block is raised slightly at its inner end, thus binding the block against the sides of the slot 13. 80 When this has been accomplished, the rail will be in the position, as shown in Fig. 2. In the rail joint the securing of the same is accomplished in the same way as will be seen in Fig. 3, the inner end of the block 14 85 engages the fish plate instead of the web of the rail and the upper flat face of the block 14 engages the under face of the nut 23 which is positioned on the bolt 24 to secure the fish plate 25 to the rail. This insures 90 a positive rail joint inasmuch as there is no possible way for the joint to work loose without the withdrawal of the block 14 from the longitudinally extending slot 21.

It is obvious that minor changes may be 105 made in the form and construction of this invention without departing from the spirit thereof. It is, therefore, not wished to confine the invention to the exact form herein shown and described, but it is wished to 110 include all such as properly come within the scope claimed.

The block 14 is of such length as to extend beyond the ends of the tie to provide means, if for any reason the block should work loose and the rail become unsteady, that the set-screw may be loosened and the block driven farther in the slot.

What is claimed, is:

In combination, a tie having a transverse slot adjacent its ends, a longitudinally extending slot at the end of said tie communicating with said first mentioned slot, a rail in said first mentioned slot, fish plates on the side of said rail, a bolt passing through

said fish plates and rail, a nut screwed on the end of said bolt and the block positioned in said longitudinally extending slot having its inner end placed beneath said nut, and means for holding said block in engagement with the under face of said nut to prevent the rotation of the same.

In testimony whereof I hereunto affix my signature in presence of two witnesses.

OCTER MAYFIELD.

Witnesses:
